COMBINATION PEDICURE TABLE AND FOOT- REST OR SIMILAR ARTICLE

Pearl M. Chancellor, Dallas, Tex.

Application December 14, 1951, Serial No. 17,725

Term of patent 14 years

(Cl. D33—14)

To all whom it may concern:

Be it known that I, Pearl M. Chancellor, a citizen of the United States, residing at Dallas, Dallas County, Texas, have invented a new, original, and ornamental Design for a Combination Pedicure Table and Footrest or Similar Article, of which the following is a specification, reference being had to the accompanying drawing, forming a part hereof.

Figure 1 is a front perspective view of a combination pedicure table and footrest or similar article embodying my new design;

The back of the table is substantially plain.

I claim:

The ornamental design for a combination pedicure table and footrest or similar article, substantially as shown and described.

PEARL M. CHANCELLOR.
